TUMBLING BARREL LINER
George E. Huenerfauth and Fred P. Green, Chicago, Ill., assignors to Crown Rheostat & Supply Co., Chicago, Ill., a corporation of Illinois

Application November 6, 1944, Serial No. 562,099
5 Claims. (Cl. 51—164)

The present invention relates to tumbling barrels and particularly to the liners employed in such barrels. In the application of Joseph Aben-
anti, Serial No. 506,667, filed October 18, 1943, there is shown a tumbling barrel of a general nature to which our invention applies. In such barrels the lining is so arranged as to be removable. It wears out rather rapidly and has to be replaced frequently. We find that, particularly in the method of finishing metal articles that utilizes a large body of material such as granite stone as a carrier for the metal articles to be finished, the wearing is such a serious problem as to cause serious delays in production while the liners are being replaced in the ends of the barrels long before the lining around the periphery is worn out.

It is the purpose of this invention to provide a novel liner construction for the barrel ends that will enable them to withstand the excessive wear to which they are subjected, thereby avoiding the necessity of such frequent replacements.

In tumbling barrels where the method of finishing hereinbefore described is practiced, the ends of the barrels have the stone and the metal articles rolling across them continuously along the steep face of the advancing mass of material. The peripheral portion of the barrel, of course, gets some wear from the particles. However, during most of the time that a particle or metal article is moving from the lower edge of the surface of the material to the point where it will again roll down across the upper face of the mass of material there is little or no wear by such a particle or article because there is no movement relatively to the barrel wall. The customary practice is to fill tumbling barrel to a level slightly above the middle thereto. This means that the central portions of the ends of the barrel have the material rolling across them continually and at the center of each end the wear is at its maximum. Our invention contemplates means to prevent the central end portions from wearing so fast.

The advantages of our invention will appear more fully from the following description and the accompanying drawing. It should be understood, however, that the drawing and description are illustrative only and should not be taken as limiting the invention except insofar as it is limited by the claims.

In the drawing:

Figure 1 is a cross sectional view through a tumbling barrel embodying our invention;

Figure 2 is a longitudinal sectional view taken substantially on the line 2—2 of Figure 1; and

Figure 3 is a perspective view of a strip of wear

resistant material having a plurality of notches and a plurality of dowel pins extending through the material and adapted to be received in notches formed in the outer shell of the barrel liner.

Figure 1 shows a tumbling barrel 10 having an outer shell 11 of sheet metal having an opening 12 adapted to be closed by a suitable closure 13.

Figure 2 shows a longitudinal section of the barrel 10 showing the liner 14 and the liner 15.

Figure 3 shows a perspective view of a strip of wear

resistant material 16 having a plurality of notches 17 and a plurality of dowel pins 18.

Referring now to the drawing, the tumbling barrel as shown in Figure 1 comprises an outer shell 10 of sheet metal having an opening at 11 adapted to be closed by a suitable closure and having a removable section at 12 which can be taken off to permit removal of the barrel lining.

The barrel peripheral lining consists of removable sections 13 extending lengthwise to the barrel and abutting each other circumferentially of the barrel to form a lining for the annular portion of the barrel. The lining for the barrel ends 14 and barrel partitions 15 comprises a plurality of wooden strips 16 cut to the proper length to fit one on top of the other in the manner illustrated in Figure 1 with spaces 17 between the strips as indicated at 16 in Figure 2. The several strips are

provided with dowel pins 18 at spaced points along their length. These pins are utilized to secure wear strips 19 in place in the spaces 17 between the several strips 16. The wear strips are constructed of a material dissimilar to the wood and

of a substantially higher resistance to abrasion. For example, the wooden strip 16 should be properly constructed of two inch thick maple walls. The wear strips are molded of a composition of Bakelite or a combination of rubber and canvas

belting or equivalent material having a high resistance to abrasion. The strips 19 actually serve as a buffer to protect the wooden strips near the center. We find that in use the wear takes place somewhat as illustrated in Figure 2. The wooden strips still wear more near the center of the end of the barrel, but as the wear gets deeper more and more of the wear is taken by the strips 19, and this results in obtaining a greater life in the lining as well as a better tumbling action because

of the engagement of the parts and the particles with the projecting strips 19. The strips 19 are notched as shown at 20 to engage the dowel pins 18 so that they cannot escape from between the adjacent wooden strips.

The great saving effected by the utilizing of the strip 19 lies in the time necessary to replace the barrel lining. It takes the men several hours to remove the lining from a barrel and replace it. The material cost of the lining is slight when compared to the cost of the work of relining.

With our improvement it is possible to more than double the life of the end linings of the barrel.

It is believed that the nature and advantages of our invention will be clear from the foregoing

description. Having thus described our invention, we claim:

1. In a tumbling barrel a lining for the ends of the barrel comprising separate wooden strips and narrow strips between the wooden strips, said narrow strips having a substantially higher resistance to abrasion than the wooden strips, whereby the excessive abrasion of the end lining near the barrel axis is counteracted by said strips.

2. In a tumbling barrel, a lining for the barrel ends comprising separate wooden strips, dowel pins extending between adjacent wooden strips and narrow strips, of a material having a much higher resistance to abrasion by the tumbling operation, interposed between the wooden strips, said dowel pins being positioned to secure the narrow strips in place.

3. In a tumbling barrel, a lining for the barrel ends comprising separate wooden strips, dowel pins extending between adjacent wooden strips and narrow strips, of a material having a much higher resistance to abrasion by the tumbling operation, interposed between the wooden strips, said narrow strips being secured to the wooden strips by dowel pins.

4. In a tumbling barrel, a lining for the barrel ends comprising separate wooden strips, dowel pins extending between adjacent wooden strips and narrow strips, of a material having a much higher resistance to abrasion by the tumbling operation, interposed between the wooden strips, said narrow strips being secured to the wooden strips by dowel pins, the narrow strips having portions cut out around said dowel pins whereby the dowel pins hold the narrow strips between the wooden strips and the adjacent edges of the narrow strips.

5. In a tumbling barrel, a lining for the ends of said barrel comprising separate wood strips, narrow strips of molded Bakelite between the wooden strips, and means carried by the wooden strips to hold the narrow strips in place.

10 6. In a tumbling barrel, a lining for the ends of said barrel comprising separate wood strips, narrow strips of rubber and canvas belting between the wooden strips, and means carried by the wooden strips to hold the narrow strips in place.

15 7. In a tumbling barrel, a lining for the ends of said barrel comprising separate wood strips, narrow strips of rubber and canvas belting between the wooden strips, and means carried by the wooden strips to hold the narrow strips in place.
